UNITED STATES PATENT OFFICE.

GEORGE RAMSEY, OF BROOKLYN, NEW YORK, ASSIGNOR TO ANCHOR CAP & CLOSURE CORPORATION, OF BROOKLYN, NEW YORK, A CORPORATION OF NEW YORK.

SINUOUS-BEAD FRICTION-SEAL.

1,386,729.

Specification of Letters Patent. Patented Aug. 9, 1921.

Application filed July 31, 1920. Serial No. 400,395.

To all whom it may concern:

Be it known that I, GEORGE RAMSEY, a citizen of the United States, residing at Brooklyn, in the county of Kings, State of New York, have invented certain new and useful Improvements in Sinuous-Bead Friction-Seals, of which the following is a specification.

This invention relates broadly to packaging and more specially to a friction cap and the package sealed by said friction cap.

The principal object of the present invention is to provide a friction cap having a sinuous sealing bead adapted for expansion when the cap is sealed on a suitable container.

A further object of the present invention is a package comprising a suitable container having substantially rigid side walls with which a friction sealing cap having a sinuous groove in the skirt thereof is adapted to cooperate to seal the package.

A still further object of the present invention is a friction cap having a substantially cylindrical skirt provided with a sealing bead having portions which are curved or inclined to the circumference of the skirt whereby forces tending to stretch the circumference likewise tend to straighten the bead.

Another and further object of the present invention is a closure cap of the character specified wherein a substantially cylindrical skirt is provided with a continuous sealing bead having portions adapted to engage the side wall of a suitable container at various zones of the container whereby the cap is adapted to accommodate the sealing zone to irregularities in the sealing wall of the container.

A still further object of the present invention is a cap of the character specified wherein a continuous sealing bead is so constructed and arranged as to form a continuous seal with a suitable vessel in such manner that the seal is formed progressively as the cap is applied whereby air may be exhausted from the cap up until the sealing is completed.

A still further object of the present invention is a cap of the character specified having a substantially cylindrical skirt portion provided with a continuous sealing bead constructed in such manner that said sealing bead engages a suitable package wall at

spaced apart intervals so that the applying forces for the cap operate locally on the bead until the seal is finally completed.

A still further and important object of the present invention is a sealing cap having a substantially cylindrical skirt provided with a continuous sealing bead constructed with depending portions adapted to contact locally with a suitable package wall in such manner that the areas of contact spread from the initial contact point until the complete bead is in contact with the vessel when the cap is being applied, thereby distributing the sealing forces over a relatively long period of the cap applying operation.

Other and further objects will in part be obvious and will in part be pointed out hereinafter in the specification following by reference to the accompanying drawings wherein like parts are represented by like characters throughout the several figures thereof.

It is realized that the present invention may be embodied in forms other than those herewith shown and described and therefore it is desired that the disclosure herein shall be considered as illustrative and not to be taken in the limiting sense.

Figure 1 is a view illustrating one embodiment of the invention comprising a cap ready to be sealed upon a suitable container;

Fig. 2 illustrates an embodiment of the invention in a slightly different form;

Fig. 3 illustrates the invention embodied in another form;

Fig. 4 illustrates the invention in a still further form; and

Figs. 5, 6, and 7 are diagrammatic illustrations of the expansion of the forms shown in Figs. 1, 2, and 4.

Heretofore in the art of friction caps there have been in general, three types; one comprising a cap having a cover portion and a straight cylindrical skirt. In this type the range of use of the cap is limited and this type of cap is usually applied to metal containers, the side walls of which are somewhat yielding. Another type of friction cap in common use is the type comprising a cover portion with a depending skirt having an inwardly projecting continuous bead, convex on the interior and concave on the exterior. This type of cap permits of a considerably greater range of utility of the cap than the straight sided skirt type for the

reason that the bead tends to expand and therefore will adapt itself to container walls of varying diameters within predetermined limits. In this type of cap the maximum 5 sealing force must be exerted simultaneously completely around the skirt of the cap because the sealing zone of the cap is a narrow circumferential zone lying substantially in a plane intersecting the skirt at right angles. 10 In view of this fact the bead makes a continuous contact with the mouth of the vessel and the entire bead must be expanded simultaneously. Another type of friction cap is that which has a plurality of separate indentations in a substantially cylindrical skirt so that the skirt of the cap contacts in 15 separate points with the side wall of the container. In this type of cap the seal is discontinuous so far as the friction zone 20 is concerned and therefore does not provide a tight seal, so that it cannot be successfully used in packaging powders, heavy liquids, or articles other than a very coarse material.

The present invention overcomes the difficulties of the known art by providing a sealing bead arranged in the skirt of a cap in such manner that the bead, at the beginning of the sealing operation, contacts with the container at spaced apart intervals so 25 that the sealing forces, to expand the bead, are applied gradually as the cap is forced in position over the container. This obviates the necessity of applying the complete sealing force at one time. The fact that 30 the sealing bead is sinuous in character permits considerably more stretching of the bead than is possible with a straight cylindrical groove, because the resilience of the metal in the cap tends to act somewhat as 35 the resilience of metal in a coil spring. 40

Furthermore, in view of the sinuous character of the bead the resiliency of the skirt of the cap is not destroyed by the bead being stretched beyond its elastic limit when the 45 cap is applied and therefore the cap may be put on or taken off frequently without danger of destroying its utility. The material from which the cap may be made may comprise thin metal, celluloid, or other elastic materials which may be suitable for packaging food products and the like.

Where the cap is used with a gasket the sinuous bead in the skirt performs the useful function of permitting trapped air to 55 escape from the package while the cap is being applied and the sealing does not take place until the cap is securely in position on the container. This function is particularly important where the cap is used with a gasket to form a hermetic seal, which is completed under a vacuum. The spaces between convolutions of the bead form outlets through which the air from the package may 60 be exhausted without danger of displacing or misplacing the cap in its position on the

container. Vacuum sealing usually takes place in a closed chamber and caps are usually loosely seated on the packages before the package and cap enter the chamber. In the old type of caps it was not infrequent 70 that the exhausting of the air from within the package would tip the cap on the package so that when the sealing operation took place the cap would be misplaced and consequently would be so distorted that a bad 75 seal would result. With the present cap the lower portions of the bead comprise supports which rest upon the mouth of the container and the spaces between the supports 80 comprise openings through which the air from the container may be exhausted without danger of displacement of the cap and furthermore the exhausting may continue after the bead has been started over the container mouth and until the final convolution 85 of the bead is forced over the edge, at which time the seal is practically completed and it is merely necessary to force the edge of the mouth of the container into engagement with the gasket which insures the maintenance of the hermetic seal. 90

Referring now to the drawings and more especially to the embodiment disclosed in Fig. 1, the cap comprises a cover portion 1 provided with a skirt 2 which may be integral with the cover portion or which may be separate therefrom. Preferably, though not necessarily, the lower edge of the skirt is provided with a rolled edge 4. The side wall of the bead is provided with a depressed bead 5 which is substantially of wavy form. This wave may comprise a continuous bead formed of joined, erect, and inverted semi-circular portions having upper crests 6 and lower troughs 7, with the part of the skirt 95 adjacent the bead being substantially plain portions 8 and 9. The container illustrated in Fig. 1 comprises a glass vessel 10, (obviously a vessel of any other material may be utilized), on which the cap is shown as 100 resting loosely prior to the sealing operation. It will be noted that the troughs 7 are resting against the mouth or end wall 11 of the container. When the cap is in this 105 position the portions 9 provide open ports 110 leading from the outer atmosphere to the interior of the container 10. It may be desirable, though in most cases it is not necessary, to provide the upper edge of the cap with a suitable gasket 12 which is adapted 115 to seal against the end 11 of the container when the cap is forced downwardly over the mouth of the container. Fig. 5 is a diagrammatic view illustrating an exaggerated form 120 of the manner in which the groove shown in Fig. 1 stretches; the full line representing the normal, unstretched groove, and the dotted line representing the groove after the 125 cap is in position on a suitable container having a substantially rigid side wall. 130

Fig. 2 illustrates a somewhat differently shaped bead wherein the configuration is that of substantially angularly disposed straight lines 14 and 15 which meet at apices 5 16 and 17. This bead functions similarly to the bead shown in Fig. 1, as is illustrated by Fig. 6, wherein the full line represents the non-stretched condition of the bead shown in Fig. 2 and the dotted line is an 10 exaggerated view of the stretched form.

Fig. 3 is another form somewhat like Fig. 2, wherein the groove is illustrated as comprising a plurality of arches 18. Preferably the apices 19 are formed by the meeting 15 or joining of the arches adjacent the lower portion of the skirt in order to comprise supports for the cap when the cap is in position on a container ready to be sealed.

Fig. 4 is a slight departure from the other 20 forms embodying the invention. The particular form illustrated in Fig. 4 is that of a representation of a chain which really in effect is substantially a double arched groove. This chain is composed of vertical links 20 25 and horizontal links 21. The stretch takes place substantially in the vertical links 20 and it will be noted the horizontal links form the connection which makes the bead continuous.

It is desirous that it be understood that 30 the beads in the caps are pre-formed during the manufacturing operations, that is, before the caps are placed in position for sealing, and that the sealing operation is performed 35 by merely forcing the cap over a suitable container by telescoping the skirt of the cap at the mouth of the container. It is also desired that it shall be clear that the gasket previously referred to is not intended to be 40 used except in such cases where it is necessary to maintain an air-tight, water-tight joint between the cap and the closure. The seal formed by the cap without the gasket is a very tight intimate seal and is quite 45 sufficient to hold many viscous liquids, although it is not sufficient to maintain a vacuum within the sealed package for any considerable length of time.

Having thus described my invention, what 50 I claim is:

1. A friction closure cap comprising a cover portion, a skirt extending at right-angles to said cover portion and a continuous sinuous sealing bead in said skirt portion.

2. A friction closure cap comprising a cover portion, a skirt extending substantially at right-angles to said cover portion and a continuous sinuous sealing bead in 60 said skirt portion, said bead being concave on the exterior and convex on the interior.

3. A closure cap comprising a cover portion, a skirt integral with said cover portion, and a wave-like sealing bead provided 65 in said skirt portion, said bead being con-

cave on the exterior and convex on the interior.

4. A closure cap comprising a cover portion, a skirt integral with said cover portion, and a wave-like sealing bead provided in 70 said skirt portion, said bead being concave on the exterior and convex on the interior, the diametrical dimensions of said bead being uniform.

5. A sealing cap provided with a cover 75 portion, a skirt integral with and extending from said cover portion, and a continuous sinuous sealing bead provided in said skirt in such manner that said sealing bead is adapted to make initial contact with spaced 80 apart portions of the container, with which said cap is utilized when said cap is initially placed upon said container.

6. A sealing cap provided with a cover portion, a skirt integral with and extending 85 from said cover portion, and a continuous sinuous sealing bead provided in said skirt in such manner that said sealing bead is adapted to rest on the edge of the mouth of the container and to make initial contact 90 with spaced apart portions of the container with which said cap is utilized when said cap is initially placed upon said container.

7. A closure cap comprising a cover portion, a skirt extending from said cover portion, a sealing bead provided in said skirt in such manner that passageways are provided between the atmosphere and the interior of a container with which said cap is utilized when a portion of the bead has 95 100 been seated against the container and whereby said bead forms a continuous seal when the cap is fully seated in position.

8. A closure cap of the character specified comprising a cover portion, a skirt adjacent 105 said cover portion and a sealing bead formed in said skirt in such manner that said skirt tends to shorten and the sealing bead tends to stretch circumferentially when said cap is applied to a substantially rigid walled 110 container.

9. The method of sealing containers and the like comprising providing a container with a substantially smooth side wall adjacent the mouth thereof, providing a closure cap having a continuous sinuous bead in the skirt thereof and applying a cap over the mouth of the container in such manner that the sealing begins at spaced apart zones on localized portions of the bead, which 115 120 zones gradually extend along the bead as the cap is applied, until a continuous seal is formed between the cap and the container.

10. The method of sealing containers and the like comprising providing a container 125 with a substantially smooth non-compressible side wall adjacent the mouth thereof, providing a closure cap having a continuous sinuous bead in the skirt thereof and applying a cap over the mouth of the con- 130

tainer by gradually telescoping the skirt of the cap and the mouth of the container in such manner that the sealing begins at spaced apart zones on localized portions of the bead, which zones gradually extend along the bead as the cap is applied until a continuous seal is formed between the cap and the container.

11. The method of sealing containers and the like which comprises providing a container with a substantially smooth side wall, providing a closure cap having a sealing bead in the skirt thereof, supporting the cap upon the mouth of the container in such manner as to provide open passageways leading from the exterior of the package to the interior thereof, and gradually closing the passageways during the sealing operation.

12. The method of sealing containers and the like which comprises providing a container with a substantially smooth side wall, providing a closure cap having a sealing bead in the skirt thereof, supporting the cap upon the mouth of the container in such manner as to provide open passageways leading from the exterior of the package to the interior thereof and gradually closing the passageways during the sealing operation and after portions of the bead are sealed against said side wall.

13. The method of sealing containers and the like which comprises providing a container with a substantially rigid side wall, providing a closure cap having a sealing bead in the skirt thereof, supporting the cap upon the mouth of the container in such manner as to provide open passageways leading from the exterior of the package to the interior thereof, and closing the passageways during the sealing operation and after portions of the bead are firmly seated against said side wall.

14. A package comprising a container having a substantially smooth side wall adjacent the mouth thereof, a cap provided with a cover portion, a skirt extending from said cover portion and over a part of the side wall of the container, and a sinuous sealing bead provided in the said skirt, with said bead in contact throughout its length with the side wall of said container and with said bead under tension so that the sealing forces are exerted against the side wall of the container.

15. A package comprising a container having a substantially smooth non-yielding side wall adjacent the mouth thereof, a cap provided with a cover portion, a skirt extending from said cover portion and over a part of the side wall of the container, and a sinuous sealing bead provided circumferentially in the said skirt, with said bead in contact throughout its length with the side wall of said container and with said bead under tension so that the sealing forces are exerted

radially against the side wall of the container.

16. A package comprising a container having a substantially smooth side wall adjacent the mouth thereof, a cap provided with a cover portion, a skirt of resilient material extending from said cover portion and over a part of the side wall of the container, and a sinuous sealing bead provided in the said skirt, with said bead in contact throughout its length with the side wall of said container and with interior diameter of said bead being slightly less than the exterior diameter of said wall so that said bead will be under tension whereby the sealing forces are exerted against the side wall of the container.

17. A package comprising a container having a substantially smooth non-yielding side wall adjacent the mouth thereof, a cap provided with a cover portion, a skirt of resilient material extending from said cover portion and over a part of the side wall of the container, and a sinuous sealing bead provided circumferentially in the said skirt, with said bead in contact throughout its length with the side wall of said container and with interior diameter of said bead being slightly less than the exterior diameter of said wall so that said bead will be under tension whereby the sealing forces are exerted radially against the side wall of the container.

18. A package comprising a container having a substantially smooth side wall, a cap provided with a cover portion, a skirt extending from said cover portion, and a continuous sealing bead in said skirt, with said sealing bead comprising a plurality of joined curved portions adapted to be stretched when said cap is forced over the mouth of the container whereby said bead is compressed against the side wall of the container.

19. A package comprising a container having a substantially smooth non-compressible side wall, a cap provided with a cover portion, a skirt extending from said cover portion, and a continuous sealing bead in said skirt, said bead being concave on the exterior and convex on the interior, with said sealing bead comprising a plurality of joined curved portions adapted to be stretched when said cap is forced over the mouth of the container whereby said bead is compressed against the side wall of the container.

20. A package comprising a container having a substantially smooth side wall, a cap provided with a cover portion, a skirt extending from said cover portion, and a continuous sealing bead in said skirt, with said sealing bead comprising a plurality of joined curved portions adapted to be slightly elongated so that said bead may be stretched when said cap is forced over the mouth of

the container whereby said bead is maintained tightly compressed against the side wall of the container when the cap is in position on the container.

- 5 21. A package comprising a container having a substantially smooth non-compressible side wall, a cap provided with a cover portion, a skirt extending from said cover portion, and a continuous sealing bead in 15
10 said skirt, said bead being concave on the

exterior and convex on the interior, with said sealing bead comprising a plurality of joined curved portions adapted to be slightly elongated so that said bead may be stretched when said cap is forced over the mouth of the container whereby said bead is maintained tightly compressed against the side wall of the container when the cap is in position on the container.

GEORGE RAMSEY.
